CLAIM

The ornamental design for a protective cover, as shown and described.

DESCRIPTION

FIG. 1 is a rear perspective view of a protective cover showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view of a protective cover, showing the second embodiment of my new design;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

In FIGS. 2 and 9, the solid perimeter line represents a boundary of the claim wherein all surfaces and features within this boundary form no part of the claimed design. The broken lines immediately adjacent the shaded surfaces represent boundaries of the claimed design. All other broken lines depict unclaimed environment. The broken lines form no part of the claimed design.
